UNITED STATES PATENT OFFICE.

GEORGE SHEARMAN, OF ATLANTIC CITY, NEW JERSEY.

GASOLINE-RESERVE DEVICE.

Application filed September 22, 1926. Serial No. 137,076.

This invention relates to improvements in motor propelled vehicles, and more particularly to improvements in the means by which the hydrocarbon engines of such vehicles are supplied with fuel and which comprises a fuel tank, a carburetor, and a tube establishing communication between the tank and carburetor.

The invention has for one of its objects to improve this means to the end that, when the fuel in the tank falls to a predetermined low level, the driver will be warned that his supply of fuel is about to become exhausted, and to attain this end I provide the tube with an inverted U-shaped loop, connect a vent tube to the top of the loop, and provide the vent tube with a normally opened valve, this structure being such that when the fuel in the tank falls to a predetermined low level the engine will cease to operate and can not again be started until the valve is opened.

The invention is hereinafter fully described and claimed, and illustrated in the accompanying drawing, wherein:

The figure is a view partly in elevation and partly in vertical section illustrating the application of the invention.

In the drawing, 1 designates the fuel tank, 2 the carburetor and 3 the tube of a well known type of means for supplying a hydrocarbon engine with fuel. The tube 3 establishes communication between the tank 1 and carburetor 2. The carburetor 2 is shown connected to the intake manifold 4 of the engine, and there is also shown the instrument board 5 of an automobile.

In accordance with my invention, the tube 3 is provided near its rear end with an inverted U-shaped loop 6 of which the top is located above the bottom side of the tank 1 and through the medium of which communication is established between the tube and tank. A vent tube 7 extends downwardly and rearwardly from the instrument board 5 to the loop 6. The vent tube 7 is secured at its rear end to and communicates with the top of the loop 6 and the front end thereof is connected to and communicates with a valve casing 8. The casing 8 is secured to the instrument board 5, and is provided with a port 9 open to the atmosphere. A valve 10 is arranged in the casing 8, and is provided with a handle 11 located at the rear side of the instrument board 5 so as

to be within convenient reach of the driver of the automobile. When the valve 10 is in opened position it establishes communication between the vent tube 7 and the port 9, and when in closed position it cuts off communication between the vent tube and port.

In practice, the valve 10 is normally open to permit the fuel, when the tank 1 contains more than the reserve supply thereof, to seek a common level in the tank and tube 7. The fuel will readily flow from the tank 1 to the carburetor 2 by way of the loop 6 and tube 3, until the level of the fuel in the tank falls below the top of the loop. When this occurs air instead of fuel will be admitted to the tube 3 by way of the valve 10 and tube 7, and as the result the engine will slow down and stop, and the driver will be thus warned that his supply of fuel is about to become exhausted. He has now a reserve supply of fuel in the tank 1, and to enable this supply to be used he must close the valve 10 and again start his engine. The closing of the valve 10 cuts off the supply of air to the loop 6, and enables the suction of the engine to siphon the fuel in the loop into the tube 3 and carburetor 2, and the engine will now operate until all the fuel has been used. The top of the tube 6 may be so positioned with respect to the bottom of the tank 1 as to cause the engine to cease operation when the fuel in the tank falls to any desired predetermined low level, and this may be done due to the fact that the tube 3 is flexible. It has been found in practice that it is only necessary to so arrange the top of the tube 6 with respect to the bottom of the tank 1 as to effect the stopping of the engine with one gallon of fuel as a reserve supply.

What is claimed is:

1. In combination, a fuel tank, a carburetor, an upstanding loop connected at one end to the tank and having its top positioned above the bottom of the tank, a tube connected at one end to the carburetor and having its other end connected to the other end of the loop, the loop constituting the sole connection between the tank and tube and the loop being flexible to permit its height to be varied so as to alter its extension above the bottom of the tank, and a valve controlled vent for the top of the tube.

2. In combination, a fuel tank, a carburetor, an upstanding loop connected at one end to the tank and having its top positioned above the bottom of the tank, a tube con-

nected at one end to the carburetor and having its other end connected to the other end of the loop, the loop constituting the sole connection between the tank and tube and the 5 loop being flexible to permit its height to be varied so as to alter its extension above the bottom of the tank, a vent tube connected at one end to the top of the loop, a valve casing secured to the other end of the 10 vent tube and extending beyond one

side of the vent tube and provided with a port open to the atmosphere, and a valve arranged in the casing and adapted when opened to establish communication between the vent tube and port and adapted when closed to cut off communication between the vent tube and port. 15

In testimony whereof I affix my signature.

GEORGE SHEARMAN.
